UNITED STATES PATENT OFFICE.

FRED D. WILSON, OF HARVEY, ILLINOIS, ASSIGNOR TO AUSTIN MANUFACTURING CO., OF CHICAGO, ILLINOIS, A CORPORATION OF ILLINOIS.

POWER-INCLINED LEANING-WHEEL GRADER.

Application filed September 25, 1924. Serial No. 739,779.

This invention relates to road graders of the type in which the traction wheels may be vertically inclined as may be required for proper operation of the machine.

5 The object of this invention is to provide power means for performing this tilting of the wheels of the machine, thus relieving the operator from the hard work which he otherwise has to perform and insuring more 10 prompt and accurate adjustment of the wheels during all conditions of operation of the machine.

The invention consists in means selectively 15 usable by the operator of the machine as it moves along the road for powerfully inclining the wheels of the road grader to such extent as may be desired, and particularly in such means, selectively controllable by an operator stationed at the single point on the 20 machine, whereby he can at will incline either both rear wheels or both front wheels of the grader. More in detail, the invention consists in means using the power of a rotating traction wheel of the machine to incline 25 said wheel and, preferably, its mate. Still more in detail, the invention further consists in numerous features and details of construction which will be hereafter more fully set forth in the specification and claims.

30 Referring to the drawings in which like numerals designate the same parts throughout the several views:

Figure 1 is a side elevation, taken on the line 1—1 of Figure 2, showing mechanism 35 illustrating this invention in its preferred form.

Figure 2 is a plan view of the machine of Figure 1.

Figure 3 is an enlarged, transverse elevation, taken on the irregular line 3—3 of Figure 1.

Figure 4 is a plan view of the mechanism of Fig. 3.

Figure 5 is an inverted, detail plan view 45 taken on the line 5—5 of Figure 4.

Figure 6 is an enlarged, rear elevation view of the machine of Figures 1 and 2, showing the wheels in tilted position.

Figure 7 is an enlarged, sectional detail 50 view on the line 7—7 of Figure 3.

Figure 8 is an enlarged, sectional detail view on the line 8—8 of Figure 3.

Figure 9 is a front view of the machine of Figures 1 and 2.

Figure 10 is a plan view taken on the irregular line 10—10 of Figure 9.

For the purposes of illustrating the invention the drawings show a more or less conventional form of grader having parallel, elongated frame members 12, sustained by front and rear axles 14 and 16, supported, respectively, by front wheels 18 and rear wheels 20. Underneath the frame and between the front and rear wheels is a more or less conventional, road working instrument 22, specifically a blade carried by the supplemental frame 24, pivoted at 26 to the front axle and selectively elevatable at opposite sides by the operator's properly conventionally manipulating wheels 28 and 30, operatively connected through suitable gearing 32, shafts 34, cranks 36 and connecting rods 38 to opposite sides of the frame. The drawings also show, intermediate between the blade 22 and the frame 24 a horizontally disposed 75 wheel 40 by which the blade 22 may be rotated to different angles crosswise of the path of travel of the machine. The parts thus far described are conventional, shown merely for illustrative purposes and do not enter 80 into the invention except as may hereafter appear.

Intermediate between front axle 14 and the front end of frame 12 is a horizontally disposed more or less conventional fifth wheel 85 mechanism 42, sustained on inclined braces 44 rising from the axle permitting conventional rotation of the axle 14 and front wheels 18 in a horizontal plane so as to allow the machine to travel around curves and corners as 90 it is propelled over the ground under any suitable source of power, as, for instance, a power tractor or horses attached to a forwardly extended member 46, rigidly attached to the fifth wheel 42.

Each end of rear axle 16 is provided with a horizontally disposed pivot 48, operatively supporting a bell crank member, one of whose arms is a horizontal stub shaft 50 and whose other arm is a vertical lever 52 extending upward inside of and approximately parallel to the adjacent wheel, the free ends of these last mentioned levers being pivotally connected to opposite ends of the connecting rod 54 substantially parallel to rear axle 16. The two members 52, axle 16 and connecting rod 54 form a parallelogram which, in a conventional manner, permits the rocking of the

wheels 20 from the upright position of Figure 3 to the inclined position of Figure 6 and to a corresponding position in which the wheels 20 are inclined to the same extent to 5 the opposite side of their normal vertical positions.

One of the members 16 and 54, in the particular case here illustrated the axle 16, carries a gear case 56 suitably secured thereto 10 by any suitable means, as, for instance, bolts 58, said gearing case journaling the horizontal shaft 60, provided with a pinion 62 meshing with a segmental gear 64 carried by the opposite of said two members, in the particular case here illustrated, connecting rod 15 54. This gear 64 is rigid with reference to connecting rod 54, being suitably secured thereto by any suitable means as, for instance, bolt 66. In conventional manner, well 20 known in the gearing art, segmental gear 64 is made with a radius equal to the distance between the pivotal connections at the ends of each bell crank arm 52 with the result that when and if pinion 62 is rotated, it causes 25 segmental gear 64 to travel over the circumference of the pinion 62 to thereby shift connecting rod 54 between the two extreme positions to which the wheels 20 may be inclined with reference to axle 16, the segmental gear 30 64 and pinion 62 being properly in mesh with each other in all positions of this movement. This relation of the parts being as stated, it is only necessary to provide means for selectively rotating pinion 62 in either direction 35 to incline the wheels 20 as the operator may desire.

For the purpose just described, shaft 60 is provided with a worm gear 68 meshing with a worm 70 on a vertically disposed shaft 72 40 carrying on its upper end, outside of the housing 56 which encloses the worm and its adjacent gear just described, sprocket gear 74, embraced by a horizontally disposed sprocket chain 76.

The gear case 56 and the adjacent parts described are preferably but not necessarily located at approximately the center of the machine and the chain 76 extends, in the particular case here illustrated, over to a point 50 adjacent to one of the rear wheels 20 where it passes around another sprocket wheel 78 on the upper end of a vertically disposed, rotatable shaft 80, journaled in another gear case 82, suitably attached by any suitable means 55 to rear axle 16. On the lower end of shaft 80 inside of gear case 82 is a horizontally disposed bevel gear 84, meshing with two vertically disposed parallel, opposing bevel gears, 86 and 88, initially freely rotatable on 60 a horizontal shaft 90, suitably journaled in the walls of gear case 82. Reciprocally but non-rotatably mounted on shaft 90, inside of case 82 and between gears 86 and 88 65 is a clutch carrier 92 having two oppositely disposed conical clutch faces 94 and 96, adapt-

ed to selectively engage at the will of the operator with corresponding conical recesses 98 and 100 in gears 86 and 88, respectively. The clutch carrier 92 is rendered non-rotatable on shaft 90 by any conventional, suitable means, as, for instance, spline connection 102. The construction is such that when the clutch carrier is moved to throw face 94 into engagement with conical recess 98, gear 86 is thereby clutched to shaft 90 to rotate gear 84, shaft 80 and attached parts, gear 88 merely rotating loosely on shaft 90 through the driving action of gear 84 and correspondingly when the clutch is so moved that conical face 96 engages conical recess 100 and gear 88, that gear drives gear 84, shaft 80 and attached parts while gear 86 is turned loosely on shaft 90. Means for throwing clutch carrier 92, so as to move the cones 94 and 96 to a selected one of the positions just described, is provided by means of an upstanding yoke 104 embracing opposite sides of the clutch, there being on the yoke pins 106 entering in conventional manner a circumferential notch 108 formed between the bases of conical members 94 and 96, the fit of the pins being such that they do not interfere with the free rotation of the clutch carrier and its cones in unison with shaft 90 but they are capable of causing yoke 104, when properly actuated, to reciprocate 95 the clutch carrier along the spline connection 102 on shaft 90 between the two clutching positions heretofore described. Yoke 104 is rigidly mounted on a rockable shaft 110, suitably journaled in the base of gear case 100 82, there being on one end of this shaft an upstanding lever 112 conveniently located adjacent to the operator's station, represented in the drawings in general by the seat 114, occupied by him when the machine is working. This lever 112 is conventionally equipped with a latch 116 adapted, when retracted, to glide over segment 120 and to otherwise enter notch 118 in the center of 105 said segment, corresponding to the position occupied by the lever 112 when the clutch carrier 92 is in the mid position shown in Figure 5 in which neither cone of the carrier is in engagement with either of the gears 86 or 88, and no tilting of the wheels is taking place. The right hand corner or end of segment 120 corresponds to the position assumed by the lever 112 when cone clutch 96 is in engagement with conical recess 100 for the purpose of causing the mechanism to tilt the 110 wheels to the inclined position shown in Fig. 6. The left hand end of the segment corresponds to the position assumed by the lever 112 when the operator has moved it to throw clutch cone 94 into engagement with conical 120 recess 98 to thus incline the wheels in the opposite direction.

On the outer end of shaft 90, nearest the adjacent wheel 20, is a bevel gear 122 meshing with a bevel gear 124 on a horizontal 125 130

shaft 126 in alignment with pivot 48 on which wheels 20 rock. This shaft 126 carries a larger bevel pinion 128 meshing with a driving bevel gear 130, rigidly attached 5 to the adjacent wheel by any suitable means, as, for instance, the bolted clamps 132, Figure 7. Shaft 126 is journaled in stationary brackets, for instance, 134 on the side of case 82 and 136 on the side of axle 16, which maintain 10 this shaft in alignment with the center of the adjacent pivot 48. The result of this construction is the important fact that pinion 128 and gear 130 are always in operative mesh with each other in all positions of inclination 15 which the operator may cause the adjacent wheel 20 to assume, as described, with the result that when the operator has manipulated lever 112 to, for instance, throw clutch members 96 and 100 into operative engagement, wheel 20 which carries gear 130 will cause said gear, through the gearing adjacent thereto, sprocket chain 76, the gearing in case 56, gears 62 and 64, to incline both 20 wheels 20 in the direction which is controlled by the particular gear 88, thus thrown into 25 operation on shaft 90. Whenever the operator sees that wheels 20 have been brought to the desired inclination by the method just described, he releases lever 112 from the inclined 30 position and swings it to the neutral or middle position, thus leaving the wheels 20 inclined and locked in that position by the friction of the gearing and, particularly, worm mechanism 68—70 which, as well understood 35 in the gearing art, acts as a lock. Whenever the operator desires to return the wheels 20 to normal, upright position or to carry them through normal to the opposite inclined position from that just described, he merely 40 swings lever 112 to the opposite inclined position to cause cone 94 to engage with face 98 whereupon the traction wheel carrying gear 130 reverses through the clutch the direction of rotation of the shaft 80 and thereby 45 causes the rotation of wheel 20 as the machine is drawn along the ground to powerfully, reversely incline both wheels 20. Whenever the wheels 20 reach the desired new inclined position, the operator moves lever 112 to central or neutral position on the segment 120, thereby causing the wheels to automatically lock themselves in said new position. When the operator desires to return the wheels from the last described up-right 55 position, he moves lever 112 to the position shown in Figure 6, thereby engaging cone 96 with face of conical recess 100 until such time as the power generated by the wheel 20, traveling over the ground, has righted both wheels, whereupon he again swings lever 112 to central or neutral position thus leaving the wheels in locked and upright 60 position.

The placing of the pivots 48, on which the 65 wheels rock, at the sides as distinguished

from the centers of the wheels, and building the power tilting mechanism in combination with them is of vast importance when all the conditions of road work by a machine of this class are taken into consideration. 70

The foregoing description giving gear 86 the ability when clutched to shaft 90 to incline the wheels in one direction and the gear 88 the ability to incline the wheels in the opposite direction is based on the assumption of the grader moving in only one direction, viz: forward. It is, however, of course obvious that if by any means not entering into this invention the grader is moved in the opposite direction, specifically backward, while either gear 86 or 88 is clutched to shaft 90, the power generated by the tractive movement of the adjacent wheel 20 will, during such backward movement, operate to incline the wheels in the opposite direction from that caused when the grader is moving forward. The possible operative combinations thus arising when the grader is capable of being propelled both forward and backward are obvious from the foregoing and appear to 90 need no detailed description. 95

The front wheels 18 of the grader are independently inclinable by the power generated by one of the front wheels through mechanism substantially identical with that applied to the rear wheels 20 and heretofore described in detail. The only essential difference is the mechanism by which the operator at his station 114 manipulates the clutch, corresponding to clutch 92 of the rear wheel mechanism, to apply the power of one of the front wheels to the inclination of both front wheels and by which such mechanism is operative, regardless of the angle of rotation of the front axle in a horizontal plane on fifth 100 wheel 42. 105

The front wheels are journaled on stub shaft-bell cranks 140—142, rockable on the end of front axle 14 on pivots 144, these parts being substantially identical with 48—50—52 110 on the rear axle. The upper ends of members 142 are connected together by a rod 146 corresponding to connecting rod 54, the same bearing a segmental gear 148 identical with gear 64. This gear 148 is operated through a worm gearing mechanism 150—152—154, contained within a housing 156, secured to front axle 114, the parts just described being identical with those at the center of axle 16 115 engaging gear 64. The worm gearing just described is connected through sprocket chain 158, identical with chain 76, to a clutch-bevel gearing mechanism contained within a case 160, mounted on axle 14, the parts being in all respects substantially identical with those in case 80 on the rear axle. The mechanism in case 160 includes a horizontal shaft 162 like shaft 90, the same being operatively connected through gears 164—166—168 and 170, corresponding to gears 122—130 heretofore 120 125 130

described. Gear 170 is rigidly attached to an adjacent front wheel 18 and gears 166 and 168 are rotatable in the axis of the adjacent pivot 144, identically as gears 124 to 128 are rotatable on the axis of adjacent pivot 48. The gearing mechanism in case 160 includes the clutch carrier 172, identical with clutch carrier 92, shiftable between bevel gears (not shown in the drawing) on shaft 162 for the same purpose and in the same manner that clutch carrier 92 is shifted. This clutch carrier is shifted by rocking a yoke 174, corresponding to yoke 104, mounted on a horizontal shaft 176, identical in function with shaft 110, and all that is necessary to cause the front wheel 18 which carries gear 170 to powerfully incline both front wheels is to properly manipulate this shaft 176 just as shaft 110 is manipulated by lever 112, as heretofore fully described.

The desired operation of shaft 176 from the operator's station is accomplished by equipping that shaft with a short, upstanding lever 178, operatively connected through connecting rod 180 and a bell crank 182 pivoted at 184 on front axle 14 to a vertically reciprocal rod 186 located in the pivotal axis on which front axle 14 rocks in a horizontal plane. This rod 186 passes through the central opening 188 in fifth wheel mechanism 42 and is operatively connected at its upper end to the free swinging end of a lever 190, rigidly mounted on the forward end of a horizontal shaft 192 extending rearwardly from the mechanism described to a journaling support 194 located in front of and reachable from the operator's station 114. At this operator's station, shaft 192 carries an operating lever 196 corresponding in all operative functions and particulars with lever 112, controlling rear wheels 20. In detail, this lever is mounted on a pivot 198 on a frame member 200. The lever rocks over a locking segment 202, having in it a notch 204, engageable by a latch 206, conventionally mounted on the lever 196. When latch 206 is in the middle or neutral notch 204, the wheels 20 are in upright position and it engages one of the other notches in each of the selected, inclined positions of the front wheels 20, exactly as lever 112 does in connection with segment 120 as heretofore elaborately described. From the foregoing, it is clear that the operator can by properly manipulating lever 196 cause the power, generated by the front wheel 18 which carries the gear 170, to incline front wheels 18 in either direction as the operator may select. The gearing in housing 156 serves to lock the wheels in selected position, inclined or upright, whenever lever 196 is in middle or neutral position on the segment 202.

From the foregoing, it will be seen that as the machine of this invention travels along the road, the operator riding thereon and at

his station 144 can, by selectively manipulating the levers 112 and 196, cause both the front and the rear wheels of the machine to assume the desired position or positions of inclination with reference to the body of the machine and the working tool 22 and that the only energy he has to expend to do this is that required to throw the clutches controlled by said levers, the power generated by the road wheels doing the real work.

Having thus described my invention, what I claim as new and desire to secure by Letters Patent is:

1. In a road machine, a traction wheel mounted for movements about an axis disposed at an angle to its axis of rotation, traction operated means for imparting said movements to the wheel, and manually controlled means for selectively connecting and disconnecting said wheel to and from the traction operated means in any position of the wheel about the first named axis.

2. In a road machine, a traction wheel mounted for movement in either of two directions about an axis at the side of said wheel disposed at an angle to its axis of rotation, traction operated means for imparting said movements to the wheel, and means for selectively causing said traction operated means to move the wheel in either direction.

3. In a road machine, a traction wheel mounted for movement in either of two directions about an axis disposed at an angle to its axis of rotation, traction operated means for imparting said movements to the wheel, and means at the will of the operator for selectively causing said traction operated means to move the wheel in either direction during tractional movement of the machine in one direction.

4. In a road machine, a traction wheel mounted for movements about an axis disposed at an angle to its axis of rotation, means operated by rotation of the wheel to impart movements thereto about the first named axis, and a manually controlled device for selectively rendering said means effective and ineffective in any position of the wheel about said first named axis.

5. In a road machine provided with an operator's station, a traction wheel mounted for movement in either of two directions about an axis disposed at an angle to its axis of rotation, means operated by rotation of the wheel to impart movement thereto about the first named axis, and a device controlled from the operator's station for selectively causing said means to move the wheel in either direction about the first named axis.

6. In a road machine, a traction wheel mounted for movement in either of two directions about an axis disposed at the side of the wheel at an angle to its axis of rotation, means operated by rotation of the wheel to impart movement thereto about the first named axis,

- and a device for selectively causing said means to move the wheel in either direction about said first named axis during rotation of said wheel in one direction.
- 5 7. In a road machine, a pair of traction wheels each mounted for movements about an axis disposed at an angle to its axis of rotation, and means operated by one of said wheels to impart said movements in unison to the wheels.
- 10 8. In a road machine, a traction wheel tilt-able in either of two directions from vertical position, traction operated mechanism for tilting said wheel, and means manipulatable by an operator on the machine for selectively causing said tilting of the wheel to take place in either direction.
- 15 9. In a road machine, a traction wheel tilt-able in either of two directions from vertical position, mechanism operated by rotation of said wheel to effect tilting thereof, and means when engaged by an operator to selectively cause tilting of the wheel to take place in either direction during rotation of the wheel in one direction.
- 20 10. In a road machine, a pair of traction wheels, each tilt-able in either of two directions from vertical position, means operated by one of said wheels to tilt both in unison, and means controlled by the operator of the machine for selectively causing said tilting of the wheels to take place in either direction.
- 25 11. In a road machine, a pair of traction wheels each tilt-able in either of two directions from vertical position, means operated by rotation of one of said wheels to tilt the wheels collectively, and means controlled by the operator of the machine for selectively causing said tilting of the wheels to take place in either direction, while the wheel operating the tilting means rotates in the same direction.
- 30 12. In a road machine, a pair of traction wheels tilt-able between vertical and inclined positions, a vertical pivotal steering connection between said wheels and the machine, and means actuated by one of said wheels for tilting both wheels in unison, said means being operative in all positions of said wheels about said vertical pivot.
- 35 13. In a road machine, a pair of traction wheels each tilt-able in either of two directions from vertical position, a vertical pivotal steering connection between said wheels and the machine, means operated by rotation of one of said wheels to tilt both wheels in unison, said means being operative in all positions of said wheels about said vertical pivot, and means selectively causing said tilting to take place in either direction while the wheel operating the tilting means rotates in the same direction.
- 40 14. A grader, comprising a frame, a pair of supporting wheels therefor, said wheels as a unit being tilt-able relative to the frame, power means operated by one of said wheels operating in all tilted positions of said wheels to tilt them, a road working tool carried by said frame, means controlled by an operator on the machine for applying and cutting off the application of said power to tilt said wheels, and means in the tilting means locking the wheels in each position assumed as the power is cut off.
- 45 15. In a road machine in combination, a frame, a pair of traction wheels connected to tilt in unison about parallel, horizontal axes, one at each side of the frame, and mechanism actuated by one of the wheels comprising a member rotatable about one of said horizontal axes for tilting said wheels.
- 50 16. In a road machine, a frame member, a traction wheel pivotally mounted on said frame member for tilting movement with respect thereto about an axis disposed at an angle to its axis of rotation, a gear wheel carried by said traction wheel, a gear wheel carried by said frame member constantly in mesh with the gear wheel carried by the traction wheel, and a connection between said second mentioned gear wheel and said traction wheel whereby rotation of the latter may be caused to impart tilting movements to itself.
- 55 17. In a road machine, a frame member, a traction wheel pivotally mounted on said frame member for tilting movement with respect thereto about an axis disposed at an angle to its axis of rotation, a gear wheel carried by said traction wheel, a gear wheel carried by said frame member constantly in mesh with the gear wheel carried by the traction wheel, and a connection between said second mentioned gear wheel and said traction wheel including means whereby rotation of the latter may be caused to impart tilting movements to itself selectively in either of two directions.
- 60 18. In a road machine, a frame member, a traction wheel pivotally mounted on said frame member for tilting movement with respect thereto about an axis disposed at an angle to its axis of rotation, a gear wheel carried by said traction wheel, a gear wheel carried by said frame member constantly in mesh with the gear wheel carried by the traction wheel, and a connection between said second mentioned gear wheel and said traction wheel whereby rotation of the latter may be caused to impart tilting movements to itself, said connection embodying a means effective to lock the traction wheel against tilting movement except by rotation of said traction wheel.
- 65 19. In a road machine, a frame member, a traction wheel pivotally mounted on said frame member for tilting movement with respect thereto about an axis disposed at an angle to its axis of rotation, a gear wheel carried by said traction wheel, a gear wheel carried by said frame member rotatable about an axis coincident with the axis about which the traction wheel is tilt-able and constantly

in mesh with the gear wheel carried by said traction wheel, and a connection between said second mentioned gear wheel and said traction wheel whereby rotation of the latter may be caused to impart tilting movements to itself.

20. In a road machine, a frame member, a pair of bell cranks pivoted at spaced points to said frame member, a traction wheel rotatably mounted on one arm of each bell crank, a rod connecting the other arms of said bell cranks, and a connection between one of said traction wheels and said rod effective by rotation of said traction wheel to shift 10 said rod longitudinally thereby to rotate said bell cranks on their pivots and thus tilt the traction wheels.
21. In a road machine, a frame member, a pair of bell cranks pivoted at spaced points to 20 said frame member, a traction wheel rotatably mounted on one arm of each bell crank, a rod connecting the other arms of said bell cranks, and a connection between one of said traction wheels and said rod effective by rotation of 25 said traction wheel to shift said rod longitudinally thereby to rotate said bell cranks on their pivots and thus tilt the traction wheels, said connection including a reversing mechanism operable to cause said traction wheels 30 to be tilted in either of two opposite directions by rotation of said traction wheels in a single direction.

22. In a road machine, a frame member, a pair of bell cranks pivoted at spaced points to said frame member, a traction wheel rotatably mounted on one arm of each bell crank, a rod connecting the other arms of said bell cranks, and a train of gears between one of said traction wheels and said rod effective by rotation of said traction wheel to shift 35 said rod longitudinally thereby to rotate said bell cranks on their pivots and thus tilt the traction wheels, said train of gears including a worm and worm wheel effective to lock the traction wheels against tilting movement 40 when rotation of said traction wheels ceases.

23. In a road machine, a frame member, a pair of bell cranks pivoted at spaced points to said frame member, a traction wheel rotatably mounted on one arm of each bell 50 crank, a rod connecting the other arms of said bell cranks, a gear wheel carried by one of said traction wheels, a gear wheel carried by said frame member in mesh with the gear wheel carried by said traction wheel, and a connection between said frame carried gear wheel and said rod effective by rotation of 55 said gear carrying traction wheel to shift said rod thereby to swing said bell cranks on their pivots and thus tilt the traction wheels. 60

In witness whereof, I have hereunto subscribed my name.

FRED D. WILSON.
